Sarah T. Aimes of Boston Massachusetts
Letters Patent No. 92955 Dated January 30, 1866
Design for Bust of Abraham Lincoln

This Schedule referred to in these Letters Patent and making part of the same.

To all whom it may concern

I, B. H. Hinman, that I, Mr. Sarah Fisher Aimes of Boston, in the County of Suffolk, and State of Massachusetts, have invented a new and improved design for a bust of the late President Lincoln; and I distinctly declare that the same is fully shown and described in the accompanying photograph, which is hereby made a part of this specification.

The invention consists in the design of a bust of the late President Lincoln, modelled and finished of the style, form, and proportions represented by fig. A. of the accompanying drawings, the same being a front view thereof.

Having thus described my invention, what I claim is,
The design for a bust as herein described and shown
